(57) **CLAIM**

The ornamental design for a physiological signal detector, as shown and described.

DESCRIPTION

FIG. 1 is a perspective view of a physiological signal detector of the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front elevation view thereof in an environment of use.

The additional broken lines shown in FIG. 8 illustrate environment and form no part of the claimed design.

The broken lines shown in FIGS. 1–8 illustrate portions of the physiological signal detector that form no part of the claimed design.
